UNITED STATES PATENT OFFICE.

ALBERT T. REID, OF LEAVENWORTH, KANSAS.

MANICURE KIT.

Application filed April 3, 1924. Serial No. 703,965.

To all whom it may concern:

Be it known that I, ALBERT T. REID, a citizen of the United States, residing at Leavenworth, in the county of Leavenworth 5 and State of Kansas, have invented certain new and useful Improvements in Manicure Kits, of which the following is a specification.

My invention relates to a manicure kit. 10 An important object of the invention is to provide a kit of the above mentioned character, which is extremely compact, complete, and convenient to use.

A further object of the invention is to 15 provide a device of the above mentioned character which is neat and attractive in appearance, and may be made sufficiently small to be conveniently carried by the user.

Other objects and advantages of the 20 invention will be apparent during the course of the following description.

In the accompanying drawings forming a part of this specification, and in which like numerals are employed to designate 25 like parts throughout the same,

Figure 1 is a side elevation of a manicure kit embodying my invention.

Figure 2 is an end elevation of the same,

Figure 3 is a central transverse section, 30 parts in elevation.

Figure 4 is a perspective view of the several elements of the kit, separated.

Figure 4^a is a side elevation of a kit embodying a second form of my invention,

Figure 4^b is a transverse section through 35 the same,

Figure 5 is a perspective view of a modified form of tray,

Figure 6 is a perspective view of a third 40 form of the invention, and

Figure 7 is a similar view of a fourth form of my invention.

Attention being called first to Figures 1 to 4 inclusive, the numeral 10 designates a 45 casing, which is preferably of an elongated elliptical form. This casing has its top open and its lower end closed by a bottom 11. The casing 10 is provided with a longitudinal partition or wall 12, rigidly secured 50 therein, and dividing the casing into upper and lower compartments. The lower compartment is adapted to receive a longitudinally movable tray 13, slideable through an opening 14 in the end wall of the casing 10. 55 This tray is preferably mounted upon tracks 15, arranged within the lower compartment

adjacent to the bottom 11. This permits of the tray moving freely and also provides a chamber or space beneath the bottom of the tray, within which suitable implements, such 60 as files, sticks or the like may be stored. This chamber is of course completely closed, when the tray 13 is in the closed position. This tray is provided with compartments 16, 17, 18 and 19, which may contain nail rouge, 65 nail white, polishing cakes, and a bottle of cuticle remover. Suitable trays may be removably held within the compartments 16, 17 and 18 while a bottle may be removably held within the compartment 19. The tray 70 13 is provided at its free end with a knob 20, by which the tray may be moved longitudinally.

The numeral 21 designates a manicure 75 buffer, embodying a handle 22, carrying a back 23, to which is secured the buffer element 24, which may be covered with chamois or the like. The buffer element is of a suitable shape and size to fit snugly within the open top of the casing 10, above the partition, thereby closing this open top. The buffer is preferably not quite as deep as the buffer compartment, providing a space 25, for the reception of implements 27, such as 80 files, sticks or the like.

In Figure 5, I have shown a modified form 85 of tray, designated as a whole by the numeral 26, and this tray has compartments 27, 28, 29 and 30 for receiving the different cosmetics or materials. The top of this tray 90 is preferably countersunk, for the reception of a lid or cover 31, hinged to the tray at 32. When this lid is in the closed position, it is flush with the upper surface of the ends 33. This tray 26 may be used in the casing 95 10, in place of the tray 13, and as the tray is equipped with a lid 31, the partition 12 could be dispensed with, although the partition 12 may be used, if desired. The cover 31 may have recesses 31', for receiving implements.

In Figure 4^a and 4^b, I have shown a modified form of the device, wherein the tray 13' is movable transversely with respect to the casing 10'. This casing has the opening in its side instead of its end. The ends of the tray 13' are of course straight so that the tray may slide, and the tray slides upon tracks 14' arranged within the casing 10'. A 105 knob 15' is secured to the side of the tray.

In Figure 6, I have shown a tray 34 which 110 is substantially identical with the tray 13,

the same receiving and holding the different cosmetics or materials. The knob 20 is omitted. Hinged to the tray 34 at 35 is a casing 36, having a flanged lower end 37, adapted to fit over and receive the top of the tray 34. The casing 36 has a bottom 38, while its top is open, for the reception of the buffer element 24 of the buffer. A lug 39 is formed upon the casing 34 to spring within a socket 40 on the flange 37.

In Figure 7, I have shown a tray 41, substantially identical with the tray 13, and receiving the several cosmetics or materials. This tray 41 is arranged beneath a casing 42, having a flanged bottom 43, for fitting over and receiving the top of the tray 41. The tray 41 has a lug 44, adapted to enter a socket 45, formed upon the flange 43. The tray 42 has a bottom 46, and the top of the tray is open for the reception of the buffer element 24 of the buffer. It is obvious that the form of the device shown in Figure 7 is similar to that shown in Figure 6, excepting that the tray and casing are entirely separable.

In the use of the first form of the device, it will be seen that the several parts of the same are securely held together and such parts may be readily and conveniently separated, for use. The tray 13 may be partly or wholly removed from the casing, so that access may be had to the tray and its contents. The buffer element is used in the ordinary manner in treating finger nails. The implements, which may be carried in the upper and lower compartments may be readily removed, for use.

In view of the foregoing description it is thought to be unnecessary to further explain the operation of the other forms of the device, which are very similar.

It is to be understood that the forms of my invention herewith shown and described, are to be taken as preferred examples of the same, and that various changes in the shape, size, and arrangement of parts, may be resorted to, without departing from the spirit of my invention, or the scope of the subjoined claims.

Having thus described my invention, what I claim is:

1. A manicure kit comprising a casing having its top open, a buffer embodying a buffer element for insertion within the open top of the casing and to be held therein, and a tray detachably connected with the casing beneath the buffer element.

2. A manicure kit comprising, a casing having its top open, a buffer embodying a buffer element for insertion within the open top of the casing and to be held therein, a tray separate from the buffer and arranged below the buffer for holding cosmetics or like material, and means connecting the tray with the casing whereby the casing normally covers the upper open end of the tray and to permit of access to the upper open end of the tray upon the relative movement between the casing and tray.

3. A manicure kit comprising a casing having its top open, a buffer including a buffer element for insertion within the open top of the casing, and a tray slidable within the casing beneath the buffer.

4. A manicure kit comprising a casing having its top open and provided at one end with an opening leading into its lower portion, a buffer including a buffer element for insertion within the open top of the casing, and a tray mounted to slide longitudinally within the casing through said opening, said tray having means for holding cosmetics or like materials.

5. A manicure kit comprising a casing having its top open and provided in its lower portion with an opening, guide means mounted within such blower portion, a tray slidable upon the guide means and movable through said opening and supported by the guide means in spaced relation from the bottom of the casing for forming a compartment for receiving and holding manicure implements or the like, said tray having means for holding cosmetics or the like, and a buffer having a buffer element for insertion within the open top of the casing.

6. A manicure kit comprising a casing having a portion thereof formed open, a buffer including a buffer element for insertion within such open portion, and a tray slidable within the casing and being adapted for holding material for treating the nails.

7. A manicure kit comprising, a casing having a portion thereof formed open, a buffer including a buffer element for insertion within such open portion, and a tray separate from the buffer and engaging the casing and adapted to be shifted to an open position with the relation to the casing.

In testimony whereof I affix my signature.

ALBERT T. REID.
